UNITED STATES PATENT OFFICE.

SETH B. HENSHAW, OF CHARLESTON, WEST VIRGINIA, ASSIGNOR TO CHARLESTON
WINDOW GLASS CO., OF CHARLESTON, WEST VIRGINIA, A CORPORATION OF WEST
VIRGINIA.

GLASS-WELL MANTLE AND CLAMP THEREFOR.

1,174,720.

Specification of Letters Patent. Patented Mar. 7, 1916.

Application filed August 5, 1915. Serial No. 43,812.

To all whom it may concern:

Be it known that I, SETH B. HENSHAW, a citizen of the United States, and a resident of Charleston, in the county of Kanawha and State of West Virginia, have invented certain new and useful Improvements in Glass-Well Mantles and Clamps Therefor, of which the following is a specification.

10 My present invention relates generally to glass furnaces, and more particularly to the wells or drawing chambers thereof as used in the drawing of vertical cylinders of glass in the manufacture of window glass, my
15 object being to form the glass well or drawing chamber by means of vertically disposed fire clay mantles having interengaging portions and to provide in connection with the furnace bindings, clamps engageable with
20 the series of fire clay mantles so disposed in order to hold the same firmly together and prevent accidental displacement.

In the accompanying drawings I have shown an arrangement whereby these objects may be well and effectively carried out, as will be better understood from the following description in which reference is made to this drawing, forming a part of this specification, and in which—

30 Figure 1 is a plan view of a well or drawing chamber constituting part of a glass furnace, and constructed in accordance with my invention. Fig. 2 is a plan of one of my improved clamps, two of which are utilized
35 in connection with each well or drawing chamber as illustrated in Fig. 1, and Fig. 3 is a detail side view of the body plate of the clamp.

Referring now to these figures, and more
40 particularly to Fig. 1, it will be seen that the well or drawing chamber indicated generally at A is constituted by a surrounding series of vertically disposed fire clay mantles B, the upper ends of which extend
45 above the roof of the furnace, and are usually supported by vertically extending bolts and the like clearly indicated at B² in Fig. 1, the upper ends of which bolts are suitably united to the superstructure of the
50 furnace in a manner which forms no part of the present invention and which when used still permits of the relative movement of the mantles B and accidental displacement thereof. It is for this purpose that I
55 provide the mantles with relatively engag-

ing ribs and recesses along their vertical side contacting edges as shown in Fig. 1 at B', and I further provide clamps in engagement with the outer mantles of the series as indicated at C and C' in Fig. 1, 60 each of these clamps being adapted for cooperation with a buckstave D and D' forming part of the furnace binding and consisting of vertically disposed channel beams in opposed pairs at opposite sides of the 65 drawing chamber, the beams facing outwardly as shown. Each of the clamps C, C', to this end includes a body plate C², one end of which is bent to engage the outer flange of one of the beams of the particular 70 buckstave in connection with which it is to be used, and further provided with an aperture c for the reception of an angle bolt E adapted to be secured therethrough in engagement with the outer flange of the other 75 beam of the same buckstave as particularly apparent from an inspection of Fig. 2, the body plate C² being thus supported in rigid connection with the buckstave with which it is used, to extend at right angles thereto. 80 Adjacent its opposite end, the body plate C² has a threaded opening through which a pressure screw bar F is mounted, the outer end F' of this bar being squared for the reception of a wrench or suitable tool, and the 85 inner end thereof being adapted to abut the outer mantle B of the series forming the wall of the well or drawing chamber as before described, so as to create a pressure through the several mantles forming this 90 wall for the purpose of thereafter maintaining the same in close contact under pressure, in order to prevent relative movement and accidental displacement.

Thus by means of the particular arrangement I have described, and by the use of the particular clamp as illustrated, I am enabled to obviate practically all difficulty now universally present in connection with the upkeep of the wells or drawing chambers of 100 glass furnaces; to entirely eliminate accidental displacement and shifting of the mantles forming the walls of such wells or chambers, and to reduce to a minimum breakage of the mantles, thereby saving considerable time, labor, and expense in substitutions and repairs. 105

I claim:

1. A clamp for holding fire clay mantles comprising a body plate having means car- 110

ried thereby at one end for detachable engagement with the outer portion only of a buckstave, and a screw bar threaded through said body plate for adjustment to engage the mantles, as described.

2. A clamp for holding fire clay mantles comprising a body plate having one bent end and an angle bolt adjacent and coöper-

ating with said bent end to detachably engage a buckstave, and a screw bar threaded through the said body plate for adjustment to engage the mantles, as described. ¹⁰

SETH B. HENSHAW.
